Fig. 5

Fig. 6

Fig. 7

Fig. 8

FIG. 1 is a side elevational view of a plastic tip pen showing our new design;

FIG. 2 is a front elevational view thereof;

FIG. 3 is a rear elevational view;

FIG. 4 is a side elevational view as it appears with the cap removed therefrom;

FIG. 5 is an enlarged top plan view of FIG. 2;

FIG. 6 is an enlarged bottom plan view of FIG. 3;

FIG. 7 is an enlarged sectional view taken on the line 7—7 of FIG. 2; and

FIG. 8 is an enlarged sectional view taken on the line 8—8 of FIG. 3.

We claim:

The ornamental design for a plastic tip pen, substantially as shown.
